FIG. 2.

UNITED STATES PATENT OFFICE.

SAMUEL EDWARD KALBACH, OF READING, PENNSYLVANIA, ASSIGNOR TO READING CRANE AND HOIST WORKS, OF READING, PENNSYLVANIA.

COMBINATION PORTABLE ROPE HOIST.

1,153,497.

Specification of Letters Patent. Patented Sept. 14, 1915.

Application filed March 4, 1915. Serial No. 11,973.

To all whom it may concern:

Be it known that I, SAMUEL EDWARD KALBACH, a citizen of the United States, residing at Reading, in the county of Berks and State of Pennsylvania, have invented 5 certain new and useful Improvements in Combination Portable Rope Hoists, of which the following is a specification.

This invention relates to improvements in 10 hoists and it applies more particularly to what is termed a combination portable rope hoist, that is, a portable hoist in which a rope and its winding drum are employed, and which may be operated either by hand 15 power or motor without the removal of any parts.

The object in the present instance is to 20 provide a simple, light portable hoist whose lifting capacity, relative to the weight of the hoist, is the maximum, one which can be constructed with a minimum cost, and one which may be operated either by a hand 25 chain wheel or through the medium of a motor connected to the power shaft of the winding or hoisting gears.

The invention consists in providing a device of the character described with a set 30 of hoisting gears located within the hoisting drum and through the medium of which rotation is transmitted to the drum, and combination hand and motor power means 35 for operating said gears for hoisting.

Briefly stated, the invention contemplates 40 a light, portable, rope hoist capable of use either by hand power or electric motor, in which the entire hoisting apparatus is confined within the hoisting drum.

The invention is more fully described in 45 the following specification and clearly illustrated in the accompanying drawings, in which:—

Figure 1 is a front elevational view of 50 my hoist. Fig. 2 is a transverse sectional view through Fig. 1 on the line A—A.

In the drawing the numeral 1 designates a 55 supporting hook by means of which the hoist may be suspended from any suitable support. This hook is attached to the housing 2, within which the hoisting drum is located.

The numeral 3 designates the hoisting 60 drum which is provided with the usual peripheral grooves 4 for the accommodation of a suitable hoisting rope 8 which rope 65 carries the usual lifting hook 5 for engage-

ment with the article to be raised or lowered by the hoist.

The numeral 10 designates the power 60 shaft; this shaft carries on its inner end, a pinion 12 and the shaft is mounted in a yoke 13. This yoke 13, together with a like or duplicate member, is mounted on the inner face of one of the housing plates 14, and a pair of studs 15 pass through both of said plates and both yokes 13 and hold the parts 65 named in relative position. The drum 3 is mounted on these yokes and rotates thereon, the one end of the drum being open, is provided with a closure plate 18 and this plate, as well as the opposite end of the drum is 70 journaled on the yokes 13 and these journals are each provided with suitable bearings 17 which may preferably be secured to the drum and rotate with it, while its inner surface bears on the periphery of the yoke. 75 The studs 15 in addition to holding the yokes, serve also as bearings for the train of hoisting gears whereby power is transmitted from the power shaft to the hoisting drum. This train of gears comprises a double gear 20 which meshes with the pinion 12 on the power shaft, through the teeth on its greater diameter, while the teeth on its smaller diameter mesh with a second double gear 22, which is mounted on the opposite 80 stud 15, and whose smaller diameter in turn meshes with a single gear wheel 25 on the first named stud. This single gear wheel 25 in turn meshes with a toothed ring 26 which is secured to the inner wall of the winding 85 drum by means of screws 28 and which rotates with said drum.

One end of the power shaft 10 projects 90 from the housing and is provided with a gear wheel 6, which is in mesh with a gear wheel 9 mounted on the side of the housing. This latter gear wheel 9 carries a hand chain 95 wheel 40, and through this wheel, when rotated in the usual manner by a chain running over its grooved periphery, power is transmitted through the power shaft 10 to the train of hoisting gears and the drum.

The interiorly toothed ring 26 fits snugly 100 inside the drum, and when worn or broken may be readily removed and replaced by 105 means of the screws 28. The closure plate 18 for the open end of the drum is secured in position thereon by means of studs 30, and when in position, serves to hold the gears against lateral movement on studs. The 110

drum being thus securely closed, serves as a receptacle for the lubricant for the gears, which lubricant may be entered through the opening 31. It is evident that by thus housing the entire hoisting mechanism within the hoisting drum I am able to provide a relatively small and light hoist and one that may be readily moved about and in which the hoisting mechanism is protected against 10 injury and thoroughly lubricated.

The gears in the train of hoisting gears are each provided with a bearing sleeve adapted to rotate with the gears, so that the only rotatable parts are the gear wheels 15 and the drum.

The numeral 50 designates an electric motor, secured to the housing and 51 the motor shaft. This shaft carries a gear wheel 52 at its extremity which is in mesh with the gear 20 wheel 9, so that, when it is desired to operate the hoist by motor power nothing need be disconnected, as the hand chain wheel will merely run idle, even though the chain be not removed therefrom. The motor is provided with a suitable brake 55, and when the 25 hoist is operated by hand, through the hand chain wheel, the motor will run idle, but the adjustment screws 56 on the brake may be released to permit its free rotation.

30 The numeral 60 designates a controller of well known form, attached to the housing opposite the motor and connected therewith by the rod 61.

The gearing on the power shaft and hand 35 chain wheel are housed and protected in a casing 70 attached to the side plate of the drum housing.

Having thus described my invention, I claim:—

40 1. In a device of the character described, the combination of a hollow winding drum, a closure plate for one end of said drum, said drum and plate having journaled bearings, a housing for said drum, yokes within 45 the housing on which the drum is rotatably mounted, studs passing through the housing and the yokes, a removable, interiorly toothed ring secured to the inner surface of

the drum, a set of gears mounted on the studs and meshing with the toothed ring, 50 a power shaft mounted in one of the yokes, a pinion on said shaft and meshing with the train of gears, a gear wheel on the opposite end of the power shaft, and means including a hand chain wheel and a motor for transmitting power through the power shaft to the drum.

2. The combination of a hollow, exteriorly grooved, open ended hoisting drum, a housing therefor, bearings within the housing on 60 which the drum rotates, a power shaft mounted in the housing, one end of which is within the drum, a pinion on the said inner end of the power shaft, a train of gears mounted within the drum and meshing with 65 the pinion, a toothed ring secured to the inner wall of the drum and in mesh with the train of gears, a gear wheel on the outer end of the power shaft, a motor carried by the housing, a gear wheel on the motor shaft, 70 an intermediate gear wheel meshing with the power shaft gear and the motor shaft gear, and a hand chain wheel carried by said intermediate gear, whereby said drum may be rotated either by hand power through the 75 hand chain wheel or by motor through the intermediate gear.

3. The combination of a hollow hoisting drum, a housing in which the drum is rotatably mounted, a train of gears mounted 80 within the drum and in gear with the interior wall thereof, a power shaft, a pinion on said power shaft in mesh with the train of gears, a motor carried by the housing, a motor shaft, a gear on the motor shaft, gears 85 for transmitting power from the motor shaft to the power shaft and hand operated means for rotating the power shaft independently of the motor.

In testimony whereof I affix my signature 90 in presence of two witnesses.

SAMUEL EDWARD KALBACH.
